UNITED STATES PATENT OFFICE.

LEONA J. CRITCHER, OF NEW YORK, N. Y.

GARMENT.

1,283,092.

Specification of Letters Patent. Patented Oct. 29, 1918.

Application filed July 17, 1917. Serial No. 180,977.

To all whom it may concern:

Be it known that I, LEONA J. CRITCHER, a citizen of the United States, and a resident of the city, county, and State of New York, have invented a certain new and useful Improvement in Garments, of which the following is a specification.

This invention relates to women's garments and specifically to that type or class 10 of garment designated as a combination garment which generally comprises a skirt portion and trouser portion, said skirt and trousers being interconnected to form a unitary structure.

15 The principal object of my invention is to provide a combined garment of the general character above mentioned which provides all the freedom of movement of the trouser yet has the appearance of the usual style of

20 skirt worn by women suitable for street wear and also for use as a house garment, bathing suit, athletic garment or the like.

My improved garment comprises an outer or skirt portion interconnected with a trouser 25 portion. These parts are so arranged and combined that unnecessary fullness or thickness of material about the waist is avoided and the garment is provided with means whereby it may be put on or removed 30 without inconvenience.

Another object of the invention is to provide a neat, graceful and perfect-fitting garment of the class referred to which will hang or drape gracefully upon the figure 35 without causing any binding on any portion of the body. My improved garment by reason of its construction affords great freedom of movement to the wearer.

With these objects, and other objects 40 which may hereinafter appear, in view, I have devised the combination of parts hereinafter described and more particularly pointed out in the claims appended hereto.

Referring to the accompanying drawing, 45 forming a part hereof,

Figure 1 is a front elevation of one embodiment of my improved garment as it appears when in use,

Fig. 2 is a front elevation of the same, 50 with the front skirt flap thrown back to disclose construction details,

Fig. 3 is a rear view of my improved garment,

Fig. 4 is front elevation of my improved

garment, the same being shown in open position to permit the entrance of the wearer; 55

Fig. 5 is a sectional view on the line 5—5 of Fig. 4, looking in the direction of the arrows,

Fig. 6 is a front elevation of a modification 60 of my invention,

Fig. 7 is a front elevation of the modification of my invention as disclosed in Fig. 6 with the front skirt flap thrown back to disclose the details of construction; 65

Fig. 8 is a rear elevation of the modification shown in Figs. 6 and 7,

Fig. 9 is a rear elevation of the trouser or drawers portion of the modification 70 shown in Figs. 6, 7 and 8, and

Fig. 10 is a sectional view on the line 10—10 of Fig. 9, looking in the direction of the arrows.

Throughout the various views of the drawings similar reference characters designate similar parts. 75

In the embodiment of my invention as disclosed in Figs. 1 to 5 inclusive, 1 indicates the skirt portion of the garment, provided at its upper edge in the usual manner 80 with a waist band 2.

At the rear of the garment, on the inner side of the skirt portion, extending downwardly from the waist band 2, to which it is secured, is a flap 3, having its side edges secured to the skirt portion 1 by the stitches 4. The lower edge of the flap 3 is unsecured to the skirt portion 1 of the garment and the trouser portion 5 of the garment has its upper edge at the rear of the garment provided with snap fasteners 6, or other detachable fastening means, which engage complementary fasteners 7 secured to the lower unsecured edge of the flap or apron 3. This construction affords what is termed a "drop-seat" construction allowing accessibility for sanitary purposes. In order that the upper or seat portion 8 of the drawers may be detached from the flap 3 and moved downwardly as hereinbefore mentioned, the sides of the trousers are unsecured to the skirt portion, as indicated at 9 (Fig. 5), but the remainder of the trousers legs, down to the point 10 are secured to the sides of the skirt portion by the seams 4. 85 90 95 100 105

The skirt portion 1 extends around to the front of the garment and is, at that part, bifurcated to form the front portions 11 of

the upper part of the trousers legs 5. The trousers legs 5 are cut away above the line 10 and this cut away portion is filled in by the parts 11 of the skirt portion whereby 5 but a single thickness of material is produced at the upper front portion of the garment and the bifurcated portions 11 form upwardly extending continuations of the legs 5. The portions 11 are secured to 10 the trousers by means of the stitches 19.

Below 10, along which the legs 5 are secured to the portions 11 by stitching 12, the lower portions 13 are secured to the trousers legs 5 and depend downwardly to produce 15 a skirted effect in the garment.

The parts 13 are shown in the drawing as being integrally formed with the upper skirt portions 11, but if desired the trousers legs need not be cut away, with the cut away 20 portions filled in by the parts 11, but instead the trousers legs can be made to extend, at the front of the garment, clear up to the waist line, in the embodiment of my invention shown in Figs. 1 to 5 inclusive, 25 or they may extend clear up to the shoulders in the embodiment shown in Figs. 6 to 10, with the flaps or extensions 13 being separate elements and secured on the line 10 and depending downwardly therefrom.

30 In the drawings I have shown the drawers legs 5 as protruding slightly below the lower edge of the skirt. If desired, of course, the trouser legs can be made much shorter so that they are at all times covered 35 by the skirt portions, and are, therefore, indiscernible. Furthermore, the lower portion of the trouser legs can be provided with an elastic to form knickerbockers, or if desired may be left open as in men's trousers, 40 or furthermore the trouser legs can be made of different material than the skirt so that should at any time the lower portion of the trousers become discernible, the appearance of a petticoat is created.

45 The contour of the garment at its front portion is like that of men's trousers and is in like manner provided with an opening or fly 13^a to allow the garment to be readily put on the wearer. The fly is closed by 50 means of the interengaging snap fasteners 14, 15 or the like.

Extending longitudinally of the garment at the front thereof, and substantially down the central line of one of the leg portions 5, 55 is a flap 16. This flap has one of its longitudinal edges secured in place by the line of stitches 17^a, and is adapted to be folded over across the garment. Adjacent its upper end and on its free edge, the flap 16 is provided with snap fasteners 17 or other detachable fastening means, and these snap fasteners 17 engage complementary fasteners 18 on the opposite leg of the garment to one side of the longitudinal central line, to 60 hold the flap in its closed position. The 65

lower portion of the flap 16 is left unsecured to allow freedom of movement. In the drawings I have illustrated the flap 16 as being an additional element, added to the garment by means of the line of stitches 70 17^a. If desired, however, the flap 16 may be merely a continuation of either of the parts 11 as will be readily understood.

From Figs. 1 and 2 of the drawings the advantages of my improved garment will be 75 readily perceived. In Fig. 2, I have shown the closure flap 16, drawn back to disclose the trouser portion of the garment, while in Fig. 1, I have shown the garment as it appears when in use. In this figure it will 80 clearly be noted that the flap 16 completely conceals the trousers portion of the garment producing the effect of a single skirt and yet producing the desirability of a combination garment, the freedom of trousers 85 and appearance of a skirt and yet providing lightness in weight, no undue thickness of material, freedom of movement of the limbs of the wearer, and accessibility for sanitary purposes. 90

Referring to the embodiment of my invention as disclosed in Figs. 6 to 10 inclusive. There I have shown my invention as applied to a full length dress. The construction therein disclosed is substantially 95 identical with that hereinbefore mentioned with respect to the embodiment of my invention shown in Figs. 1 to 4 inclusive, except that the garment is provided with an upper portion and is thus supported from 100 the shoulders.

In this construction the front, upper portion of the garment is cut away, from the neck-band 20 downwardly as at 21 to produce an opening for the entrance of the 105 body of the wearer. This opening 21 combined with the fly 13 allows the garment to be readily put on or removed. The closure flap 16, in this embodiment of my invention extends substantially the full length of the 110 garment and its detachable securing means 17 and 18 extend from the neck band 20 or the shoulders instead of from the waist band.

A belt 22 is provided on the garment. 115

From the foregoing, it is obvious that my invention is not to be restricted to the exact embodiments herein shown, but is broad enough to cover all structures coming within the scope of the annexed claims. 120

Having described my invention, what I claim is:—

1. A garment comprising a skirt, a pair of trouser legs within said skirt having their upper part combined with the skirt, the front 125 part of the skirt being bifurcated and having its front upper portion serving as an upward extension of the trouser legs with its lower portions unattached to said legs and forming downwardly depending flaps 130

to cover the lower ends of said trouser legs, and a foldable flap on the garment adapted to fold to conceal the trouser legs at the front of the garment.

- 5 2. A garment comprising a skirt, a pair of trouser legs within said skirt, the rear portion of said trouser legs extending upwardly within the skirt with its upper end detachably secured therein, the front upper 10 portion of the skirt being bifurcated and serving as an upward extension of the trouser legs, the two lower portions of said bifurcated front part of the skirt forming flaps depending downwardly over the lower 15 portions of the trouser legs and a foldable flap on the garment adapted to fold to conceal the trouser legs at the front of the garment.
3. A garment comprising a skirt, a pair 20 of trouser legs within said skirt, portions of said skirt at the front of the garment being bifurcated forming upward extensions of the trousers and flaps depending downwardly over the lower ends of the trouser 25 legs, a fly on said upward extension of the trousers extending downwardly from the waist line of the garment, a flap secured to the inner side of the garment at the rear thereof and extending downwardly below 30 the waist line, detachable fastening means on said flap adjacent its lower edge, coacting fastening means on the upper edge of

the seat portion of the garment and a closure flap secured at one side of the front portion of the garment said flap being foldable 35 across the garment and adapted to be detachably secured to the other side.

4. A garment comprising a skirt, a pair of trouser legs within said skirt, portions of said skirt at the front of the garment being 40 bifurcated forming upward extensions of the trousers, other portions of said skirt at the front of the garment forming flaps depending downwardly over the lower portions of the trouser legs, a flap secured to 45 the inner side of the garment at the rear thereof and extending downwardly with its lower edge below the waist line of the garment, detachable fastening means on said flap, a seat portion on the trousers extending 50 upwardly to meet said flap, detachable fastening means on the seat portion for engaging the fastening means on said flap, a longitudinally extending flap at the front of the garment, said flap having one of its side 55 edges secured to the garment at the front thereof on a line to one side of the central longitudinal line of the garment, the free end of said flap being adapted to be detachably secured to the garment on the opposite 60 side of its central longitudinal line.

Signed at the city, county and State of New York, this 16th day of July, 1917.

LEONA J. CRITCHER.
